PLANT CONTAINER

Jerome D. Monkarsh, 105 Lincoln Road, Brooklyn, N.Y.

Filed Mar. 7, 1963, Ser. No. 73,864

Term of patent 3½ years

(Cl. D35—3)

I claim:

The ornamental design for a plant container, substantially as shown.
